DYNAMOELECTRIC MACHINE

Stanley E. Tomkinson, Fort Wayne, Ind., assignor to
General Electric Company, a corporation of New
York

Filed May 20, 1966, Ser. No. 2,367

Term of patent 14 years

(Cl. D26—5)

FIG. 1

FIG. 2

FIGURE 1 is a top plan view of a dynamoelectric machine showing my new design;

FIGURE 2 is a side elevational view of the dynamoelectric machine as seen from the bottom in FIGURE 1;

FIGURE 3 is a side elevational view of the dynamoelectric machine as seen from the top in FIGURE 1;

FIGURE 4 is an end elevational view as seen from the left in FIGURE 1; and

FIGURE 5 is an end elevational view as seen from the right in FIGURE 1.

I claim:

The ornamental design for a dynamoelectric machine, as substantially shown and described.
